US0D1012143S

(12) **United States Design Patent** (10) **Patent No.:** **US D1,012,143 S**
(45) **Date of Patent:** **** Jan. 23, 2024**

(54) **DELIVERY ROBOT**

(71) Applicant: **TOYOTA JIDOSHA KABUSHIKI KAISHA**, Toyota (JP)

(72) Inventor: **Masashi Akahori**, Nissin (JP)

(73) Assignee: **TOYOTA JIDOSHA KABUSHIKI KAISHA**, Toyota (JP)

(**) Term: **15 Years**

(21) Appl. No.: **29/801,940**

(22) Filed: **Aug. 2, 2021**

(30) **Foreign Application Priority Data**

Feb. 4, 2021 (JP) ..... 2021-002417 D

(51) **LOC (14) Cl.** **15-99**

(57) **CLAIM**

The ornamental design for a delivery robot, as shown and described.

DESCRIPTION

FIG. 1 is a front perspective view of a delivery robot showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The claimed design is indicated by the relatively dark portions in the figures. The relatively light portions protruding from the top form no part of the claimed design.

1 Claim, 8 Drawing Sheets
